United States Patent Office

Des. 196,984
Patented Nov. 26, 1963

196,984

JUG

Richard L. Platte, Ann Arbor, Mich., assignor, by mesne assignments, to The Dow Chemical Company, Midland, Mich., a corporation of Delaware

Filed Nov. 13, 1962, Ser. No. 72,460

Term of patent 14 years

(Cl. D58—5)

FIG. 1

FIG. 2

Des. 196,984

PAGE 2

FIG. 3

FIG. 4

FIG. 5

FIG. 6

FIG. 7

FIG. 8

FIGURE 1 is a perspective view of a jug, showing my new design;

FIGURE 2 is a top plan view thereof;

FIGURE 3 is an end elevation thereof showing the end away from the handle;

FIGURE 4 is an end elevation thereof showing the end having the handle;

FIGURE 5 is a bottom plan view thereof;

FIGURE 6 is a side elevation thereof;

FIGURE 7 is a fragmentary section taken on the line 7-7 of FIGURE 3; and

FIGURE 8 is a fragmentary section taken on the line 8-8 of FIGURE 7.

I claim:

The ornamental design for a jug, as shown.

UNITED STATES PATENT OFFICE
CERTIFICATE OF CORRECTION

Design No. 196,984

November 26, 1963

Richard L. Platte

It is hereby certified that error appears in the above numbered patent requiring correction and that the said Letters Patent should read as corrected below.

In the grant, lines 2 and 3, for "assignor, by mesne assignments, to The Dow Chemical Company, of Midland, Michigan, a corporation of Delaware," read -- assignor, by direct and mesne assignments, of one-half to The Dow Chemical Company, of Midland, Michigan, a corporation of Delaware, and one-half to Hoover Ball and Bearing Company, of Ann Arbor, Michigan, a corporation of Michigan, --; line 13, for "The Dow Chemical Company, its successors" read -- The Dow Chemical Company and Hoover Ball and Bearing Company, their successors --; in the heading to the printed specification, lines 3 to 5, for "assignor, by mesne assignments, to The Dow Chemical Company, Midland, Mich., a corporation of Delaware" read -- assignor, by direct and mesne assignments, of one-half to The Dow Chemical Company, Midland, Mich., a corporation of Delaware, and one-half to Hoover Ball and Bearing Company, Ann Arbor, Mich., a corporation of Michigan --.

Signed and sealed this 12th day of May 1964.
